US0D1013751S

(12) **United States Design Patent** (10) **Patent No.:** **US D1,013,751 S**
(45) **Date of Patent:** **** Feb. 6, 2024**

(54) **DELIVERY ROBOT CHASSIS**

(71) Applicant: **Ninebot (Beijing) Tech Co., Ltd.**,
Beijing (CN)

(72) Inventors: **Yafei Liu**, Beijing (CN); **Chao Xue**,
Beijing (CN); **Weining Xi**, Beijing (CN)

(**) Term: **15 Years**

(21) Appl. No.: **35/514,769**

(22) Filed: **Jun. 21, 2022**

(80) **Hague Agreement Data**

Int. Filing Date: **Jun. 21, 2022**
Int. Reg. No.: **DM/222039**
Int. Reg. Date: **Jun. 21, 2022**
Int. Reg. Pub. Date: **Jul. 22, 2022**

(30) **Foreign Application Priority Data**

(57) **CLAIM**

The ornamental design for a delivery robot chassis, as shown and described.

DESCRIPTION

The patent or application file contains at least one drawing executed in color. Copies of this patent or patent application publication with color drawing(s) will be provided by the Office upon request and payment of the necessary fee.

1. Delivery robot chassis
2. Delivery robot chassis

1.1 : Front
1.2 : Back
1.3 : Left
1.4 : Right
1.5 : Top
1.6 : First perspective view
1.7 : Second perspective view
2.1 : Front
2.2 : Back
2.3 : Left
2.4 : Right
2.5 : Top
2.6 : First perspective view
2.7 : Second perspective view

Bottom views of designs 1 and 2 are omitted since they are not easy to be seen or cannot be seen during usage.
The portions shaded in a transparent yellow wash in the figures form no part of the claimed design.

1 Claim, 14 Drawing Sheets
